CLAIM

The ornamental design for a wire management clip, as shown and described.

DESCRIPTION

FIG. 1 is a top, front, left-side perspective view of a wire management clip;

FIG. 2 is a top view thereof;

FIG. 3 is a bottom view thereof;

FIG. 4 is a right-side view thereof;

FIG. 5 is a left-side view thereof;

FIG. 6 is a front view thereof;

FIG. 7 is a back view thereof; and,

FIG. 8 is a top, front, left-side perspective view thereof, shown in a position of use with an unclaimed rail.

The broken lines in the drawings depict portions of the wire management clip that form no part of the claimed design. The additional broken lines in FIG. 8 depict environmental subject matter that forms no part of the claimed design.
